BREADBOX WITH BREADBOARD

Paul Knudson, Box 37, Occidental, Calif. 95465

Filed Dec. 7, 1972, Ser. No. 313,111

Term of patent 14 years

Int. Cl. D7—07
U.S. Cl. D7—82

FIG.
1.

FIG.
2.

FIG. 3.

FIG. 4.

FIG
.5.FIG
.6.FIG
.7.

FIG. 1 is a front perspective view of a breadbox with breadboard showing my new design;

FIG. 2 is a front perspective view thereof, showing the door and board being in an open position;

FIG. 3 is an end elevational view, both ends being identical;

FIG. 4 is a front elevational view;

FIG. 5 is a top plan view;

FIG. 6 is a rear elevational view; and

FIG. 7 is a cross-sectional view taken on line 7—7 of FIG. 1.

I claim:

The ornamental design for a breadbox and breadboard, as shown and described.
